(57) **CLAIM**

The ornamental design for a golf ball, as shown and described.

DESCRIPTION

FIG. 1 is a front perspective view showing the front and side of a golf ball;

FIG. 2 is a front elevation view thereof;

FIG. 3 is a rear elevation view thereof;

FIG. 4 is a top plan view thereof;

FIG. 5 is a bottom plan view thereof;

FIG. 6 is another perspective view thereof; and,

FIG. 7 is another perspective view thereof.

The broken lines are directed to environment and form no part of the claimed design.

1 Claim, 4 Drawing Sheets
